CLAIM

We claim a new ornamental design for a lid for a container, as shown and described.

DESCRIPTION

FIG. 1 is a perspective view of a lid for a container according to our new design.

FIG. 2 is a rear elevational view of the lid for a container of FIG. 1, the front elevational view being a mirror image thereof;

FIG. 3 is a top plan view of the lid for a container of FIG. 1;

FIG. 4 is a left side elevational view of the lid for a container of FIG. 1;

FIG. 5 is a bottom plan view of the lid for a container of FIG. 1; and,

FIG. 6 is a right side elevational view of the lid for a container of FIG. 1.

The dashed lines in FIGS. 1-6 represent environment and are for illustrative purposes only and do not constitute part of the claimed design.
